ALEXANDER E. WILLIAMS, OF CLEVELAND, OHIO.

COLLAPSIBLE CORE.

1,162,961.

Specification of Letters Patent.

Patented Dec. 7, 1915.

Application filed January 20, 1915. Serial No. 3,345.

To all whom it may concern:

Be it known that I, ALEXANDER E. WILLIAMS, a citizen of the United States, residing at Cleveland, in the county of Cuyahoga and State of Ohio, have invented a certain new and useful Improvement in Collapsible Cores, of which the following is a full, clear, and exact description, reference being had to the accompanying drawings.

10 This invention relates to collapsible cores of the kind used in producing hollow concrete walls of the "poured" variety.

The object of the invention is to provide a core of the above character that is extremely simple of construction and very cheap of production, and at the same time, highly efficient in the accomplishment of its purpose.

Further objects comprehended by my invention are the provision of a core of the collapsible type that may be very easily contracted and expanded; to provide, in such a core, means whereby the core may be handled and suspended in either its contracted or expanded condition; and the provision of a collapsible core the entire surface of which is moved away from the walls of the core-formed cavity upon the operation of the collapsing mechanism. A feature of importance is the manner in which I utilize certain parts of the collapsing mechanism for strengthening the comparatively thin metal shells of which the core is formed.

In the accompanying drawing I have shown a collapsible core wherein the foregoing objects are attained; and while I will proceed to describe the same in detail, I wish to be understood as not limiting myself to the structural details thereof further than is required by the terms of the annexed claims, and is rendered necessary by the state of the prior art.

In the drawing, Figure 1 represents a substantially central vertical section through the core, the plane of the section being indicated by the line 1—1 of Fig. 3; Fig. 2 is a vertical section, at right angles to Fig. 1, on the line 2—2 of the former figure; and Fig. 3 is a horizontal section on the line 3—3 of Fig. 1, the last figure being on a somewhat enlarged scale as compared to Figs. 1 and 2.

Taking up a detailed description of the invention by the use of reference characters, 1 and 2 represent opposed shells that are substantially U-shape in cross section, and

the side walls of the shell 1 are spaced far enough apart to receive between them the corresponding walls of the shell 2. Spaced some distance from the vertical edges of the shell 1, and secured to the inner surfaces of the side walls thereof, are the narrower flanges of the angle plates 3 and 4, the wider flanges whereof extend inward and overlie each other, as clearly shown in Fig. 3. Bearing the same relation to the shell 2, 60 are a pair of angle plates 5 and 6. As will be observed from Figs. 1 and 2, the angle plates extend from near the bottom of the core to within a short distance of its upper end, and these angle plates serve to materially stiffen the shells 1 and 2. Near their upper and lower ends, the overlying flanges of each pair of angle plates are provided with oppositely inclined slots 3^a, 4^a, etc., as shown in Fig. 2.

Secured within the curved portion of the shell 1, and near its lower end, is a plate 7 having a slot 7^a that is inclined inward and downward from the upper end of the plate and terminates at its lower end in a substantially vertical portion 7^b. A similar plate 8 is fastened within the curved portion of the upper end of the shell 1 and has a slot 8^a that is inclined from its upper end inward and downward, according to the inclination of the portion 7^a of the slot of the former plate, and this slot has a straight portion 8^b at its lower end. The plate 8 extends some distance above the top of the core and is there provided with a horizontal slot 8^c, the bottom side of which is preferably in the plane of the top edge of the shell. The shell 2 is fitted with plates 9 and 10, precisely like the plates 7 and 8, respectively, of the shell 1.

The inclined slots of the angle plates 3 to 6 are in horizontal alinement with the slots of the plates 7 to 10, and all of the slots are of substantially the same vertical extent.

11 and 12 are bars which extend through the alining upper and lower slots, respectively, of the angle plates 3 to 6, and the ends of these bars terminate in lateral, rounded studs 13 which pass through the slots of the plates 8 to 10, and are provided with washers 14 that are held in place by the cotter pins 15.

16 is a yoke which straddles the upper ends of the angle plates and extends down alongside the bars 11 and 12, and the verti- 110

cal branches of the yoke are fastened to said bars by the bolts 17.

When it is desired to collapse the core, the yoke 16 is drawn upward, whereupon the studs of the bars 11 and 12 will traverse the inclined slots of the plates 8 to 10, and the body portions of the bars will rise within the slots of the angle plates 3 to 6, causing the shells to approach each other.

10 and, at the same time, drawing their side walls inward. In this manner all parts of the shells 1 and 2 are moved inward and the cross sectional area of the core is reduced. Attention is here directed to the par-

15 ticular cross sectional shape of the shells. It will be seen that their side walls, some distance back from their vertical edges, are parallel to each other, while the walls converge from these portions toward the round-

20 ed portion of the shell. By reason of this, when the core is being contracted, the slightest movement of the shells toward each other will cause the aforesaid converging portions to immediately leave the concrete.

25 The core is expanded by reversing the foregoing operation, and when the studs 13 of the bars 11 and 12 occupy the substantially vertical portions of the slots in the plates 8 to 10, the core is very effectually

30 locked against contraction. It is often found desirable, in concrete construction, to support the cores from the upper edges of the side forms, with the cores in expanded condition. This may be very readily accom-

35 plished in my improved core by inserting pipes or cylindrical bars through the slots 8^c and 10^c of the plates 8 and 10, respectively, allowing the ends of the bars or pipes to rest upon the upper edges of the side forms.

40 The fact that the supporting bars or pipes are cylindrical and act, therefore, as rollers, allows the core to be suspended even in its collapsed condition and expanded thereafter by the depression of the yoke 16, the

45 supporting bars rolling with respect to the upper walls of the slots 8^c and 10^c, and upon the upper edges of the side forms. Further-

more, should it be found desirable to lift the forms at any time while they are ex-
50 panded, this may be readily accomplished by inserting a suitable rigid handling device into the slots 8^c and 10^c. Where the bars 11 and 12 operate within the slots of the angle plates 3 to 6, the upper and lower edges

55 of the bars are rounded as shown at 11^a and 12^a, respectively.

In order that the core may be handled or suspended by the yoke 16 while the core is expanded, I provide means for locking the 60 shells of the core to the relatively movable internal part. Such means is illustrated in the drawing as a pair of hooks 18, one of which is pivoted at 19 to each of the wider flanges of the angle plates 4 and 6, the hooks 65 being arranged to be thrown over the bar 11

when the same is in the lower ends of the various slots through which it operates. It is obvious that, when the hooks embrace the bar 11 and retain it in its lowest position with respect to the slots, the core may be 70 lifted by means of the yoke without effecting the cross sectional area of the expanded core.

Having thus described my invention, what I claim is:—

75 1. A collapsible core comprising a pair of opposed shells that are substantially U-shape in cross section and arranged so that portions of opposed sides of one shell overlie the outer surfaces of portions of the other, a plate secured to and projecting inward from each side of one shell, each plate having a portion which overlies a portion of the other and provided with a slot, the slots of the respective plates being oppositely inclined and adapted to register, a plate secured within the curved portion of each shell and having a slot that is oppositely inclined with respect to the slot in the other, and a member having slot engaging portions that are arranged to traverse the various slots when said member is moved.

2. A collapsible core comprising a pair of opposed flexible shells that are substantially U-shape in cross section and arranged so that portions of opposed sides of one shell overlie the outer surfaces of portions of the other, a plate of substantially the length of the shell secured to and projecting inward from each side of each shell, the opposed plates of each shell overlying each other and having oppositely inclined registering slots, a plate secured within the curved portion of each shell and having a slot that is oppositely inclined with respect to the slot in the corresponding plate of the other shell, and a member extending through the registering slots of the first mentioned plates and having slot engaging portions that are arranged to traverse the slots of the second mentioned plates.

3. A collapsible core comprising a pair of opposed shells, a plate secured to and projecting inward from each side of each shell, the opposed plates of each shell having oppositely inclined registering slots, and a member extending through registering slots and having connection with the opposed shells.

4. A collapsible core comprising a pair of opposed shells, a plate secured to and projecting inward from each side of each shell, the opposed plates of each shell having oppositely inclined registering slots, a plate secured within the curved portion of each shell and having a slot that is oppositely inclined with respect to the slot in the corresponding plate of the other shell, the slots of the last mentioned plates terminating at one end in parallel portions, and a member

having slot engaging portions that are arranged to traverse the various slots when said member is moved.

5. A collapsible core comprising a pair of opposed shells, a plate of substantially the length of the shell secured to and projecting inward from each side of each shell, the opposed plates of each shell having oppositely inclined registering slots, a plate secured within the curved portion of each shell and having a slot that is oppositely inclined with respect to the slot in the corresponding plate of the other shell, a member having slot engaging portions that are arranged to 10 traverse the various slots when said member is moved, and an independent supporting member secured to each shell whereby the core may be suspended.

6. A collapsible core comprising a pair of opposed shells, a plate secured to and projecting inward from each side wall of each shell, the opposed plate of each shell having oppositely inclined registering slots, a plate secured within the curved portion of each shell near the lower end thereof and having a slot that is oppositely inclined with respect to the slot of the corresponding plate of the other shell, a similar plate secured within the curved portion of each shell near its upper end and having a portion which projects above the upper edge of the shell, each plate having a slot which corresponds in inclination to the slot of the lower plate of its respective shell, the slots of said upper and lower plates terminating at one end in portions that are parallel to each other, each of the upper plates having a horizontal slot, and a member having slot engaging portions that are arranged to traverse the various inclined slots when said member is moved.

7. A collapsible core comprising a pair of opposed shells, a plate of substantially the length of the shell secured to and projecting inward from each side wall of each shell, the opposed plates of each shell having oppositely inclined registering slots, a plate secured within the curved portion of each shell near the lower end thereof and having a slot that is oppositely inclined with respect to the slot of the corresponding plate of the other shell, a similar plate secured within the curved portion of each shell near its upper end and having a portion which projects above the upper edge of the shell, each plate having a slot which corresponds in inclination to the slot of the lower plate of its respective shell, each of the upper plates having an opening above the plane of the upper edge of the shell, and a member having slot engaging portions that are arranged to traverse the various inclined slots when said member is moved.

8. A collapsible core comprising a pair of opposed shells, a plate secured to and pro-

jecting inward from each side of each shell, the opposed plates of each shell overlying each other and having slots near their upper and lower ends that are arranged to register, the corresponding slots of the two plates being oppositely inclined, a plate secured to the curved portion of each shell near its lower end and having a slot that is oppositely inclined with respect to the slot of the corresponding plate of the other shell, the slots of the last mentioned plates being in substantially the plane of the lower slots of the first mentioned plates, a plate secured within the curved portion of each of the shells near its upper end and having a portion which projects above the upper end of the shell, each of the upper plates having a slot that corresponds in inclination to the slot of the lower plate of its respective shell, said upper plates having openings in their upper ends above the plane of the upper edges of the shells, the inclined slots of the upper plates being in substantially the plane of the upper slots of the first mentioned plates, bars which extend through the upper slots of the first mentioned plates and having studs at their ends which occupy the slots of the upper plates, a bar extending through the lower slots at the first mentioned plates and having studs at their ends which occupy the slots of the lower plates, and a yoke that extends across the upper ends of the first mentioned plates and having branches that depend within the shells and are secured to the aforesaid bars.

9. A collapsible core comprising a pair of opposed shells, a plate secured to and projecting inward from each side of each shell, the opposed plates of each shell overlying each other and having slots near their upper and lower ends that are arranged to register, the corresponding slots of the two plates being oppositely inclined, a plate secured to the curved portion of each shell near its lower end and having a slot that is oppositely inclined with respect to the slot of the corresponding plate of the other shell, the slots of the last mentioned plate being in substantially the plane of the lower slots of the first mentioned plate and terminating at their lower ends in substantially parallel portions, a plate secured within the curved portion of each of the shells near its upper end, each of the upper plates having a slot that corresponds in shape to the slot of the lower plate of its respective shell, the inclined slots of the upper plates being in substantially the plane of the upper slots of the first mentioned plates, bars which extend through the upper slots of the first mentioned plates and having studs at their ends which occupy the slots of the upper plates, a bar extending through the lower slots of the first mentioned plates and having studs at their ends which occupy the 130

4
slots of the lower plates, and a yoke that extends across the upper ends of the first mentioned plates and having branches that depend within the shells and are secured to the aforesaid bars.

10. A collapsible core comprising a pair of opposed shells, a plate secured to and projecting inward from each side of each shell, the opposed plates of each shell overlying each other and having slots near their upper and lower ends that are arranged to register, the corresponding slots of the two plates being oppositely inclined, a member movable longitudinally of the shells, and members having connection with the first mentioned member and with the opposed shells and having portions which occupy the registering slots of the aforesaid plates.

11. A collapsible core comprising a pair of opposed shells, a plate secured to and projecting inward from each side of each shell, the opposed plates of each shell having oppositely inclined registering slots, a member movable longitudinally of the shell, and members having connection with the first mentioned member and extending through registering slots of the aforesaid plates and having connection also with the shells.

12. A collapsible core comprising a pair of opposed shells, a plate secured to and projecting inward from each side wall of each shell, the opposed plates of each shell having oppositely inclined registering slots, a plate secured within the curved portion of each shell and having a slot that is oppositely inclined with respect to the slot in the corresponding plate of the other shell, a member having slot engaging portions that are arranged to traverse the various inclined slots

when said member is moved, and means for locking said member against movement with respect to the shells.

13. A collapsible core comprising a pair of opposed shells, a plate secured to and projecting inward from each side wall of each shell, the opposed plates of each shell having oppositely inclined registering slots, a plate secured within the curved portion of each shell and having a slot that is oppositely inclined with respect to the slot in the corresponding plate of the other shell, a device having slot engaging members that are arranged to traverse the various inclined slots when said device is moved, and a hook pivoted to one of the first mentioned plates of each of the shells and arranged to embrace certain of the slot engaging members of the aforesaid device when said members are at one end of the slots.

14. A collapsible core comprising a pair of opposed shells, each shell having side walls that are connected by a curved portion, the opposed side walls of each shell being parallel vertically and horizontally for some distance from their vertical edges and then converging to the aforesaid curved portion, said curved portion being of lesser radius than half the distance between the parallel portions of the side walls, and mechanism within the shells which operates to move the shells toward each other and the sides of the respective shells inward.

In testimony whereof, I hereunto affix my signature in the presence of two witnesses.

ALEXANDER E. WILLIAMS.
